UNITED STATES PATENT OFFICE.

MILES W. QUICK, OF TITUSVILLE, PENNSYLVANIA.

METHOD AND APPARATUS FOR OPERATING OIL-WELLS.

1,369,049.

Specification of Letters Patent. Patented Feb. 22, 1921.

Application filed March 25, 1918, Serial No. 224,478. Renewed July 15, 1920. Serial No. 396,591.

To all whom it may concern:

Be it known that I, MILES W. QUICK, a citizen of the United States, residing at Titusville, in the county of Crawford and 5 State of Pennsylvania, have invented new and useful Improvements in Methods and Apparatus for Operating Oil-WellS, of which the following is a specification.

This invention relates to methods and apparatuses for operating oil producing wells as will be hereinafter fully described and pointed out in the claims.

The method at present employed in recovering the oil from earth formations through 15 penetrating wells involves a release of the pressures of the volatile vapors in the well, so as to dissipate the energies which should be utilized as the expansive force for maintaining the production of the well.

20 I propose through the general well-operating method hereinafter illustrated and described to accomplish the expulsion of elastic earth-saturating fluids during the limited periods in which their innate energies are 25 being released with maximum degrees of expansive force and the exertion of negligible refrigerating influences on unexpelled saturations with the idea of approximating a maximumly efficient expansive displacement of such fluids.

In carrying out my invention I preferably prevent to a large extent the separation of the gasolene vapors from the oils in the well and consequently increase the production of 35 gasolene from the oils expelled.

It will be understood the explosive energy of fluid hydrocarbons must be obtained from the adjacent earth formations. It is my purpose to conserve this energy and to utilize 40 it in the most efficient manner for the expulsion of said fluids.

In carrying out my invention I preferably interpose a resistance to the escape of vapors from the well so as to maintain a tension on 45 the vapors in the earth saturations at all times. I periodically release this resistance so as to vary this tension and induce a flow toward the penetrating well. It will be understood that if the well is entirely closed 50 and the vapors confined that the tension on said vapors will reach an ultimate tension depending on the depth and condition of the well. I preferably maintain a maximum tension by my method more nearly this ultimate tension than zero tension and I preferably confine the range of variations in this

tension when the resistance to the escape of vapors is reduced to less than fifty per cent. of the ultimate tension. Giving an example, assuming the ultimate tension to be one hundred pounds, I would prefer to periodically accumulate a maximum tension of above fifty pounds, as for instance, seventy-five pounds and to confine the variation to less than fifty per cent. of the ultimate tension, or with the ultimate tension assumed to less than fifty pounds, so that the maximum range of variation under these conditions would be from seventy-five to twenty-five pounds. Preferably I maintain both the maximum and the minimum tensions nearer the ultimate than zero tension. In the example assumed of one hundred pounds ultimate tension I would prefer to maintain a maximum tension approximating the ultimate tension and a minimum tension of about thirty per cent. below this, or seventy pounds. One reason for confining the variation within these limits and pressures is to maintain the stratification of the intruding earth waters and the hydrocarbon earth saturations by maintaining a pressure on said earth saturations equal to the difference in specific gravity between said intruding waters and the hydrocarbon earth saturations.

In the accompanying drawings I have illustrated an apparatus in accordance with my invention and suitable for carrying out my process as follows:

Figure 1 shows a section of an oil well.

Fig. 2 a central section of an automatic resistance interposing and releasing device.

Fig. 3 a section on the line 3-3 in Fig. 2.

1 marks the well, 2 the saturated earth formation, 3 a casing extending below water sources in gas wells, below gas-bearing formations in oil wells, and serving as a reservoir and conduit of vapors to the surface, 4 a pump, 5 a tubing extending from the pump to the top of the well, 6 a sucker rod, 7 a pump jack, 8 a cable for operating the pump and jack, 9 a discharge from the tubing, 10 a casing head, 11 a discharge from the casing head, 12 a resistance interposing and releasing device and 13 a valve at the discharge side of the resistance interposing device. These parts, with the exception of the resistance interposing device are of any ordinary construction used in oil wells.

The resistance interposing device 12 comprises the body 14, diaphragm 15 dividing

the body into the inlet side 16 and discharge end 17. A valve opening surrounded by a valve seat 18 is arranged in the diaphragm and a valve disk 19 operates on said seat. 5 A stem 20 extends from the valve disk through a piston 21, the stem being secured in the piston by a nut 22. The piston operates in a cylinder 23. The piston has a central expansion chamber 21^a. The stem 10 20 is provided with a longitudinal passage 24 which leads from a radial passage 25 in the valve disk, the passage 25 being opened and closed by the opening and closing of the valve. The passage 24 leads to the 15 radial passages 26 which open into the expansion chamber 21^a. A bypass 27 is arranged in the walls of the cylinder 23 and is adapted to carry the fluid delivered to the expansion chamber past the end of the 20 piston 21 when it has been moved to its lower position opening the valve disk 19.

In order to control the interval of time necessary to reduce the difference in pressures on the two ends of the piston 21 I 25 provide the needle valve 28 by means of which the size of the passage 24 may be adjusted as desired.

A stem 29 extends from the opposite side of the valve disk from the stem 20, and an 30 abutment in the form of a nut is provided on said stem. A nut 30 rests on a spring 31. The spring is preferably made up as shown: A series of spring elements 32 have the outer 35 ends of their arms resting on division rings 33, the lower of said rings resting on a shoulder 34 in a housing 34^a. Division rings 35 are arranged between the springs adjacent to the stem 29 and communicate to each of the spring elements 32 the movement 40 of the nut 30. In this way each of the elements 32 is flexed with a movement of the stem 29. Where greater tension is desired a greater number of elements 32 are interposed thus stiffening the spring, and 45 where less tension is desired some of these elements are removed. The spring pressure may also be adjusted by means of the nut 30.

The operation of the device so far as described is as follows: It will be noted that 50 the area of the piston 21 is greater than the area of the bottom of the valve disk 19, and as these two surfaces are exposed to the same elastic pressure there is a preponderance of downward force by reason of the 55 greater area of the piston. When the pressure reaches the desired pre-determined maximum this preponderance is effective in overcoming the resistance of the spring 31 and the valve 19 is opened. As the piston 60 moves downwardly it uncovers the bypass 27 permitting the passage of fluid by way of the passages 25, 24 and 26 and bypass 27 to the opposite end of the piston 21. As soon as the pressure on the lower end of 65 the piston has reached a degree approxi-

mating the pressure at the inlet side 16 the effective pressure on the piston is so reduced that the spring closes the valve. The interval of time necessary to produce this operation is controlled by the size of the communicating passages, and this can be adjusted by the needle valve 28 so that any period of exhaust through the resistance interposing device may be had that will accomplish the most efficient results. This will depend 75 upon the conditions within the well, and the capacity of the discharge passages to exhaust the vapors during the period the valve is opened. In this way the resistance to the expulsion of fluids from earth formation can be reduced to the point that taking 80 into consideration the lowering of temperature will release the maximum expansive-expulsive forces of the fluids acted upon.

In operating wells penetrating formations 85 saturated with either high or low gravity fluid aggregations in normal earth temperature states, maximum degrees of expansive-expulsive-force are available for release, and the shorter the time-periods and the lesser 90 the attenuation of products during their expulsion, the greater the expansive displacement per unit of expended energy, the lesser the volumes of heat transformed into energy, and the derivation of heat from unexpelled residuals. An important result possible of realization by the operation of wells by the method herein disclosed, therefore, is the provision of means for the conservation 95 of the energies of unexpelled saturat- 100 ing volumes, and maintaining them in states available for release with maximum degrees of expulsive efficiency. Preferably as before stated, the reduction in pressure is such as to permit the expansion of only what is ordinarily considered the noncondensable gases, thus retaining the gasoline in more or less liquid form with the oils so that such gasoline may be readily separated from such oils after their expulsion from the well. 110

In order to vent the chamber 21^a I provide the port 36 which is uncovered by the piston when the valve is closed. This port leads to a pipe 37 connected with the discharge end 17. I preferably provide a 115 check 38 in the pipe to prevent back-flow.

In order to vent the end of the cylinder 23 I provide a passage 39. The capacity of this passage is controlled by a needle valve 40. It will be understood that this 120 passage should be a minute one forming a mere leak so as to vent the end of the cylinder without in ordinary practice materially changing the action of the device. If desired, however, this vent may be utilized to some extent to vary the interval between exhaust periods.

In order to assure a complete closure by the disk 19 I prefer to provide a flexible annular disk 41, ordinarily of leather which 130

operates on a seat 41^a. It will be observed that the leather covers the joint formed by the metallic surfaces of the valve disk and valve seat. I also prefer to provide the cylinder 23 with a flange 42 which is secured to a face 43 on the body 14 by screws 44. I provide the gasket 45 in the joint thus formed, and make the inner periphery of the gasket of slightly less diameter than the cylinder 23 so that the piston 21 seats on the projecting portion of the gasket when the valve is closed.

I also preferably provide a back-pressure neutralizing piston 46 which is secured to the stem 29, and operates in a cylinder 47 communicating with the discharge end 17 of the device. This piston 46 is preferably of the same area as the upper side of the valve disk so that the tendency to move the valve by reason of the pressures in the discharge side of the device is neutralized.

What I claim as new is:—

1. The method of operating oil wells which consists in interposing resistance to the escape of vapors and varying said resistance by alternately increasing and reducing the same, thereby accumulating a maximum tension in the well nearer the ultimate tension of the vapors of said well than zero tension, and the variation having a range of less than fifty per cent. of the ultimate tension of the vapors in the well.

2. The method of operating oil wells which consists in interposing a resistance to the escape of fluids, thereby maintaining a tension on the fluids nearer the ultimate than zero tension, and varying the resistance by alternately increasing and reducing the resistance.

3. The method of operating oil wells which consists in interposing a resistance to the escape of vapors therefrom, varying the resistance by alternately increasing and reducing the same, and limiting the reduction in resistance to a point to maintain the well pressure above the fully released pressure of the well.

4. The method of operating oil wells which consists in interposing a resistance to the escape of vapors therefrom, varying the resistance by alternately increasing and reducing the same, and limiting the variation in pressure to less than fifty per cent. of the maximum pressure.

5. The method of operating oil wells which consists in interposing a resistance to the escape of vapors and varying the resistance by alternately increasing and reducing the resistance, the period of reduction being time controlled.

6. The method of operating oil wells which consists in interposing a resistance to the escape of vapors, while varying the resistance by alternately increasing and reducing the same and proportioning the vari-

ations with relation to the maximum expansive explosive force incident to the available heat energies.

7. The method of operating oil wells which consists in interposing such a resistance to the escape of vapors, while varying the resistance by alternately increasing and reducing the same to confine the vaporization to the more volatile constituents of the oil, and proportioning the variations with relation to the maximum expansive explosive force for the expulsion of products from the penetrated oil bearing formations incident to the available heat energies.

8. The method of operating oil wells which consists in interposing a resistance to the escape of vapors, varying the resistance by alternately increasing and reducing the same and controlling the variation as to time with relation to the maximum expansive energies incident to the constituents of the earth saturations and their maximum tension.

9. The method of operating oil wells which consists in interposing a resistance to the escape of vapors, varying the resistance by alternately increasing and reducing the same and controlling the variation as to range with relation to the maximum expansive explosive energies acting with said vapors and incident to the constituents of the earth saturations and their maximum tension.

10. The method of operating oil wells which consists in interposing a resistance to the escape of vapors, varying the resistance by alternately increasing and reducing the same and controlling the variation as to range and time with relation to the maximum expansive explosive energies acting with said vapors incident to the constituents of the earth saturations and their maximum tension.

11. The method of operating oil wells which consists in removing the accumulated oil from the well, interposing a resistance to the escape of vapors from the well and varying the resistance by increasing and reducing the same, said variations having a different frequency than said oil removals.

12. The method of operating oil wells which consists in removing the accumulated oil therefrom at intervals, the frequency of which is determined by the accumulation of oil, interposing a resistance to the escape of vapors from the well, and varying the resistance by increasing and reducing the same at intervals determined by the vapors in the well.

13. The method of operating oil wells which consists in interposing a resistance to the escape of vapors from the well, thereby maintaining a tension on the fluids in said well and permitting the vaporization of only the more volatile of said fluids, and periodi-

cally varying said resistance to induce a flow of oil from the saturated earth formations toward the well.

14. The method of operating oil wells which consists in interposing a resistance to the escape of vapors from the well, thereby maintaining a tension of the fluids in said well and preventing the vaporization of the gasolene constituents of the oil, and periodically varying said resistance to induce a flow of oil from the saturated earth formations toward the well.

15. The method of operating oil wells which consists in interposing a resistance to the escape of vapors from the well, thereby maintaining a tension on the fluids in said

well and preventing the vaporization of the gasolene constituents of the oil, and periodically varying said resistance to induce a flow of oil from the saturated earth formations 20 toward the well, and removing the oil with its gasolene constituents from the well.

16. In an apparatus for operating oil wells, the combination of means for confining the expansive fluids in the well; and 25 devices acting with said means and operating periodically and to a pre-determined extent as to time to release the tension of said fluids.

In testimony whereof I have hereunto set 30 my hand.

MILES W. QUICK.
